CLAIM

The ornamental design for a hearing protector, as shown and described.

DESCRIPTION

FIG. 1 is a perspective view of a hearing protector showing our new design;

FIG. 2 is a right side view thereof;

FIG. 3 is a left side view thereof;

FIG. 4 is a front view thereof;

FIG. 5 is a top view thereof;

FIG. 6 is a bottom view thereof;

FIG. 7 is a rear view thereof; and,

FIG. 8 is another perspective view thereof shown in a folded position.

Portions of the drawings shown in broken lines do not form part of the claimed design.

1 Claim, 4 Drawing Sheets
